UNITED STATES PATENT OFFICE.

JAMES WALTER DAVIS AND ELIJAH CLARK BROWN, OF WEST, TEXAS.

KNEE-PAD.

SPECIFICATION forming part of Letters Patent No. 554,776, dated February 18, 1896.

Application filed October 25, 1895. Serial No. 566,884. (No model.)

To all whom it may concern:

Be it known that we, JAMES WALTER DAVIS and ELIJAH CLARK BROWN, citizens of the United States, residing at West, in the county 5 of McLennan and State of Texas, have invented a new and useful Knee-Pad, of which the following is a specification.

This invention has for its object to provide an improved pad to be worn upon the knee 10 when picking cotton, berries, or attending to low plants, and aims to provide a device for excluding dampness from the knee and protecting the latter from injurious contact with stones, roots, and other unyielding obstructions usually met with when performing the 15 work herein indicated.

A further purpose of the invention is the construction of a device which can be applied to the lower portion of the limb and secured 20 thereto in a positive manner without occasioning inconvenience or causing annoyance to the person wearing the same, and which is adjustable within certain limits to adapt it to different-sized persons.

25 Other objects and advantages are contemplated and will be apparent as the nature of the invention is better understood, and to this end the improvement consists in certain details and novel combinations of parts, which 30 hereinafter will be more fully set forth, illustrated, and claimed.

The drawings illustrate an embodiment of the invention, although slight changes in the form, proportion, and minor details of construction 35 may be resorted to without departing from the spirit of the invention, and in said drawings—

Figure 1 is a perspective view of the improved device. Fig. 2 is a top plan view 40 thereof; Fig. 3, a transverse section on the line X X of Fig. 2. Fig. 4 is a bottom perspective view of the pad disconnected from its mountings.

Referring to the drawings, in which the same 45 reference-numerals indicate corresponding and like parts in all the figures, 1 denotes the pad proper, which comprises a metal portion 2 conformed to the knee portion of the limb and a suitable backing 3, of sheep-skin 50 or upholstery of any kind, so as to provide a cushion for the knee, thereby rendering comparatively easy and comfortable the otherwise

irksome task of picking cotton, berries, &c. The metal portion 2 excludes dampness and protects the knee from injury in the event of 55 a stone, root, or other unyielding object coming beneath and opposite to the knee. For the sake of lightness the part 2 is constructed of sheet metal, which is provided in the form of an oblong blank, and which is curved downwardly between its edges, and which has one end slotted and the portions bordering upon the said slit bent or curved upwardly, so as to extend in front of the knee when the device is in operative relation. The backing or 65 cushion 3 may be secured to the inner or upper side of the metal part in any desired or convenient manner.

Side bars 4, of wood or other light material, extend in parallelism and are adapted to come 70 upon opposite sides of the limb, and are of such a length as to extend from the ankle to the knee, and their upper ends are formed with slots 5, which receive the fastenings 6, by means of which the pad is adjustably connected to the said side bars. 75

The fastenings 6 are bolts which extend through the side portions of the pad midway of their ends, and which have their threaded extremities projecting through the slots 5 and 80 supplied with binding-nuts 7, by means of which the pad is held in the required adjusted position. The lower ends of the side bars have connected therewith a suitable harness for attaching them to the foot of the wearer, 85 and this harness in the present instance consists of a heel-strap 8 and a strap 9 for passing beneath and around the instep of the foot, so as to prevent vertical displacement of the device after the latter has been properly 90 adjusted to the limb. Straps or tapes 10 are attached to the sides of the pad near its front or top end and are designed to pass around the limb immediately beneath the knee, so as to complete the attachment of the device to 95 the limb.

It is obvious that a person engaged in picking cotton, berries, treating low plants, &c., will wear a pad upon each knee, thereby securing the full benefits of the invention. The 100 means employed for connecting the pad to the side bars admit of the pad being adjusted longitudinally relative to the said side bars as well as being turned upon the fastenings

to any required angle to suit the ease and convenience of the person wearing the contrivance.

5 The device can be worn either in a kneeling or upright position without inconveniencing the wearer, and this is one of the salient features and principal objects of the invention, as will be readily comprehended from what has been said.

10 Having thus described the invention, what is claimed as new is—

15 1. A device of the character and for the purpose herein specified, comprising side bars, means for securing them to the human limb immediately below the knee and to the foot, a knee-pad, and means for adjustably connecting the knee-pad to the said side bars, substantially as and for the purpose set forth.

20 2. In a device of the character and for the purpose specified, the combination of side bars having slots at one end, means for securing the side bars to the human limb, a pad, and fastenings operating in the slots of the side bars to secure the pad to the said side bars in an adjusted position, substantially as 25 and for the purpose set forth.

3. In combination, side bars having slots at one end, a harness applied to the opposite end of the side bars for securing them to the

foot of a person, a pad, fastenings operating 30 in the slots of the side bars to adjustably connect the pad therewith, and straps attached directly to the pad and adapted to be passed around the limb immediately beneath the knee, substantially as and for the purpose 35 described.

4. The herein shown and described device for the purpose set forth, comprising a knee-pad, straps applied to the front end of the pad, side bars having longitudinal slots at 40 one end, fastenings operating slidably and tiltingly in the said slots and having connection with the sides of the pad to connect it in a tilting and sliding position with the side bars, a heel-strap secured to the opposite ends 45 of the side bars, and a foot-strap to engage with the lower portion and instep of the foot, substantially in the manner and for the purpose specified.

In testimony that we claim the foregoing 50 as our own we have hereto affixed our signatures in the presence of two witnesses.

JAMES WALTER DAVIS.
ELIJAH CLARK BROWN.
